UNITED STATES PATENT OFFICE

161,425

BATHROOM FIXTURE

Alton A. Cleverdon, New Rochelle, N. Y.

Application April 8, 1950, Serial No. 9,054

Term of patent 7 years

(Cl. D4—3)

To all whom it may concern:

Be it known that I, Alton A. Cleverdon, a citizen of the United States, residing at 1 Elizabeth Road, New Rochelle, State of New York, have invented a new, original, and ornamental Design for a Bathroom Fixture, of which the following is a specification, reference being had to the accompanying drawing, forming a part hereof.

The single figure is a perspective view of a bathroom fixture, showing my new design.

I claim:

The ornamental design for a bathroom fixture, substantially as shown.

ALTON A. CLEVERDON.
